OUTSIDE DOOR FOR RAILWAY CARS

Bryan J. O'Neill, Peoria, Ill.

Application May 4, 1934, Serial No. 723,862

24 Claims. (Cl. 20—27)

This invention pertains to improvements in grain door for railway cars. More particularly it relates to outside doors for use on railway cars of the type used for shipping grain, the door of my invention being of a form for use on the outside of the car, made wholly of metal, and employed in the capacity of a "grain door" for replacing the quite well known wooden "inside door".

10 One of the objects of the invention is to provide an outside grain door that will be thoroughly proof against leakage of grain from the car on which it is installed.

15 Another object lies in providing a door having separate parts movable relatively to each other by which the loading and unloading of a car is facilitated, such door being constructed and furnished as a complete unit ready for installation on a car, the latter requiring no special structures or changes for accommodating it.

20 Another object is to provide an outside grain door parts of which can be locked relatively and relatively to the car, and by the use of a single mechanism.

25 Other objects and advantages will be apparent from the following description aided by the appended drawings forming part hereof, it being stated at the outset that changes of minor nature may be made without departing from the spirit 30 of the invention or from the terms of the claims to follow.

Figure 1 is a side elevation of a portion of a railway car showing the door of my invention in position at the doorway.

35 Figure 2 is a transverse section of parts of the structure as produced on line 2—2, Figure 1.

Figure 3 is likewise a transverse section of parts shown in Figure 1 produced on line 3—3 thereof.

40 Figure 4 is a horizontal section of part of the wall of a car at the doorway thereof with parts of my grain door stationed therat.

Figure 5 is a vertical transverse section of a part of a car together with the door of my preferred construction.

45 Figures 6 and 7 are horizontal sections of parts of the door produced on lines 6—6 and 7—7, respectively, of Figure 1.

Figure 7a is a top edge view of part of a lower door section.

50 Figure 8 is an end elevation of a socket portion of an operating worm.

Figure 9 is an end elevation of parts of the door and members for operating one of such parts, and

Figure 9a shows in perspective part of a main door section.

Part of a railway car is denoted by the character 1 over the doorway of which is any usual door-supporting track 2. Suspended from the track is a main door section 3 by means of hanger portions 4 as parts of the latter, in this instance, and lying in the same plane therewith, said section being spaced at its upper edge some distance from the track, and whose lower edge, also, is spaced well above the floor 5 of the car. In addition to the said hangers 4 the door is provided with depending portions 6 at each of its vertical edges, and these may also be parts thereof and lie in the same plane therewith. These portions 6 at their lower ends are upturned into hooks 7, Figures 5 and 9, to engage beneath a flange on the lower side of a guide-member 8, for example, fixed in position below the doorway, and along which the said hooks are freely movable.

The space above the main door section 3 is designed to be closed by a second door section 9 having a hanger 10, for example, for suspending one thereof from the said track 2, the lower edge of this said section slidably engaging opposite surfaces of the section 2 at its top edge, said edge being preferably formed with an offset as in Figures 5 and 9 to hang more directly in line with the track 2, it being observed that a grain-tight joint is preserved between the associated edges of the sections.

The space below the section 3 is closed by a third door section 11 which lies just behind and inward therefrom as in Figure 5, preferably occupying a position between said section 3 and an inner reinforcing sheet 3' secured to the latter and covering substantially the entire inner face thereof but spaced therefrom for the purposes stated, the character 3², Figure 4, denoting a spacing member at one edge of these parts.

A stud 12 is fixed in an extension 6' of one of the depending portions 6, for instance, of the door section 3 and extends to and through one end of the section 11, and a worm-wheel 12' is affixed thereto. Said section 11 is loosely mounted on said stud and is adapted to turn about the same, there being mounted on said section 11 between ears 13 thereon a worm 14 meshing with said worm-wheel 12'. Preferably the worm shaft terminates in a squared end 13' to receive an operating wrench, not shown, said squared end lying deep within a tubular portion 13² so that a wrench of a special socket type is required to reach it.

On one of the jambs at the doorway is secured

an L-shaped strip 15, Figure 4, so stationed as to receive the edges of the door sections 3, 9 and 11, bracing them against the load of grain and preventing leakage of the latter.

5 In order that loss of grain may be prevented at the opposite jamb for the doorway a trapping means is provided. That is to say, in Figures 6 and 7 at said jamb a strip 16 is secured, said strip having an extension 17 spaced from and paralleling the outer wall surface of the car. The section 9, Figure 6, has at its vertical edge a return hook portion 18 which in the closed position of said section engages behind the said extension 17. Again, in Figures 7 and 7^a the main door section and the section 11 both have the hook portions 3³ and 11¹, respectively, for a like purpose, a grain tight joint resulting throughout the entire height of the doorway.

Since the upper section 9 of the door is slidable 20 it can be opened to permit entrance of a grain spout through to load the car, and "sampling" of the grain can be done through the same opening. When it is desired to sample the grain nearer the floor of the car this can be done through an opening 20 in the lower section 11 which is normally closed by a part next to be described. By pivoting section 11 it can be raised to discharge the grain through the action of the worm and worm-wheel mechanism previously described.

30 One of the purposes of the invention is to lock the sections 3 and 9 at one operation, when "sealing" the door as in usual railroad practice. Secured on the lower portion of the section 3 is a bracket 21 pivoted on which is a lever 22 whose lower end in its swinging movement may either overlie or expose the said opening 20, said opening being closed, of course, in the locked and sealed position of such lever. Pivoted to the lever near its upper end is one end of a bar 23 whose other end is pivotally connected to a lever-arm 24 on a rock-shaft 25 journaled on said section 3, said rock-shaft extending to the upper section 9 and having at its end an arm 26 arranged to enter an opening 27 in a plate 28 fixed on said section 9. The lever 22 carries a latch 29 to engage the bracket 21, and also carries a hasp 30, for instance, to engage any usual staple 31 through which a pin or bolt 32 may extend to receive the customary railway seal 33.

50 In the position of the named parts shown in continuous lines in Figure 1 it will be seen that the opening 20 is covered. And in this position, also, the arm 26 of the rock-shaft 25 engages in the opening 27 of the plate 28. However, when in the position shown in dotted lines the said opening lies exposed and the arm 26 is free of the plate 28 so that the upper section 9 may be shifted. The latch 29 serves to prevent chance opening of the door as a whole when the hasp 30 60 is disengaged from the staple 31 as might occur during switching operations.

While the lower section 11 may, of course, be also locked by a slight change from the structure shown it is in effect locked through the worm and worm-wheel operable only by the special wrench already mentioned so that miscreants cannot easily cause trouble.

65 It is to be observed that whereas certain of the operating parts for the section 11 have heretofore been mounted upon the car itself they are in this instance carried on the door entirely. Thus the door is a complete unit ready for installation on the car.

70 It is to be observed that since the worm-wheel 12 is fixed with respect to the main door section

3, the section 11 will be moved about the stud 12 by the worm which travels around the said worm-wheel during rotation.

My door structure, in effect, adds the upper and lower sections 9 and 11, respectively, to the outside door in common use and thereby an all-purpose door results in that both a grain door, by special structures, and a door for ordinary merchandise can be accommodated. The usual outside door can only, of course, be used for one purpose, being fit only for commodities other than grain.

Again, the door of my invention by providing the upper and lower door sections in an outside door permits ready loading and unloading of the grain thoroughly appreciated by persons having full knowledge of such matters.

Due to the fact that such an operating arrangement as the worm and worm-wheel is used by which great power is possible, the door section 11 20 can be readily raised even when the weight and pressure of grain lies against it. On the other hand, because of the fact that the said section passes between the portions 3, 3' of the main door section the weight of grain and the friction there- 25 of against said section 11 is constantly decreased as the latter moves up behind the inner portion 3'. Thus the section is even more easily operated, re- quiring less and less power the higher it is lifted.

30 I claim:

1. In an outside door for railway cars, a main door section disposed to cover the middle height of the doorway of a car, a door section pivotally mounted on the main door to cover the space below the same and shiftable parallel to said main door, and mechanism for swinging the pivotal section, such mechanism being jointly mounted on the door sections.

2. In combination with the wall of a railway car, a unitary structure including a main door section, a mounting to carry the same by which it is free to travel in a direct line lengthwise of the car free of the same, said section arranged to close the door opening in said wall but exposing a portion of the full width of the door opening at the floor of the car, and a second door section pivotally mounted at one end upon the main door section at one side of the said door opening in position to rise and fall at the opening, the pivotal mounting for the second door section arranged to maintain that section substantially parallel to the main section and permit it to be shifted vertically, the two door sections being free to be demounted as a unit from the car.

3. In combination with a railway car and a door supporting mounting, a door structure including a main door section carried by the mounting adapted to travel across the doorway of the car, said section being arranged to create an opening at the doorway above the floor of the car, a second door section mounted upon and wholly supported by the main door section adapted for closing the opening at the floor, and means on the main door section for carrying the second section and guiding it in a plane parallel to the main door section, the thus constituted door structure being bodily demounted as a unit from the car and mounting.

4. In combination with the wall of a car having an open doorway, of a mounted and guided main door section adapted to span the doorway and spaced at its lower edge above the floor of the car, the same adapted to be moved horizontally to expose such doorway, and a second door

section for closing the space below said edge of the main door section at said floor, and means pivotally mounting the said second section upon said main section, said means comprising two intermeshing portions separately mounted on the

5 sections, one adapted to operate the other whereby the said second section is tilted upon and with respect to the main section.

5. An outside grain door for railway cars consisting of a main movable door section mounted upon the outside of such car and spaced at its upper and lower edges respectively from the upper and lower extremes of the door opening of said car, and separate door sections mounted on 10 said main section each for closing one of the resultant spaces, one of the sections being slideable upon said main section and the other being pivoted on the latter and swingable in a plane paralleling the same, all of the sections being comprised in a single structure.

6. The invention according to claim 5 with which is included means for operating one of the sections.

7. A grain door for railway cars consisting of a structure applicable to the outer side of the car for closing the door-opening thereof, such structure including a main door section covering part of the height of said door-opening between the upper and lower extremes thereof, a door section in the opening above the main door section, a door section pivoted on and wholly carried by the main door section and covering the opening below the said main section, and means carried by the two last named sections for operating the pivoted section, all of the named parts being comprised in a single unit.

8. In an outside grain door for railway cars, a main door section for covering the middle height of the doorway exposing below it the entire width 40 of said doorway, a door section pivotally mounted on the main door section adapted to close the space below the same, and mechanism for operating the pivoted section comprising a worm-wheel fixed with respect to one of the door sections, and a worm journaled on the other of said door sections and engaging said worm-wheel.

9. In an outside grain door for railway cars, a main door section for covering the doorway in that space thereof lying just above the floor of the car below the main section, a door section pivotally mounted on the main door section to overlie said space of the doorway, and mechanism for swinging the pivoted section on its pivot comprising a worm-wheel fixed with respect 50 to the main door section, and a worm journaled on the said pivoted section and engaging said worm-wheel.

10. A grain door for mounting upon the outer wall of a railway car, including a main door section, an upper and a lower door section mounted upon the main door section and movable with respect to the same parallel to the plane thereof each adapted to overlie opposite edges of the main door section, and a member at each of the jambs 60 of the doorway with which the sections engage in the closed position of the door for providing grain tight joints between the sections and the said outer wall of the car.

11. In combination with the wall of a railway car, a door for closing the doorway thereof comprising a mounted movable main section arranged to cover part of the said doorway, a second mounted companion door section movable relatively to the main section arranged also to 70 cover part of such doorway, and means mounted

on one of the sections arranged to have movement relative thereto adapted to engage the other section fixing both sections relatively, and means to secure the first named means with respect to the wall of the car.

5 12. A grain door for mounting upon the outer side of the wall of a railway car, including a main door section, an upper door section movable with respect to the main section, means mounted on the main door section adapted to be secured with respect to the car-wall, means to engage the said upper door section, and a connection between the two said means adapted to communicate movement from one to the other.

13. A grain door for mounting upon the outer side of the wall of a railway car including a main door section, a lower door section below the said main section and having an opening therein, a lever mounted on the main door section adapted to be secured with respect to the car wall, said 15 lever being arranged to cover said opening of the said lower door section in the secured position of said lever.

14. A grain door for mounting upon the outer side of the wall of a railway car, including a main door section, an upper door section movable with respect to the main section, means mounted on the main door section adapted to be secured with respect to the car wall, means to engage the said upper door section, a connection between the two 25 said means adapted to communicate movement from one to the other, a lower door section having an opening therein, the first named means adapted in its secured position to overlie said opening.

30 15. A grain door structure including a main section, a door section slidably engaging one edge of said main section, and a door section pivotally mounted on the said main section swingable parallel to the plane of the same in close relation thereto adjacent the edge thereof lying 35 opposite that having the slidable section.

40 16. A grain door structure including a main section, a door section slidably engaging one edge of the same, a door section pivotally mounted on the said main section arranged to overlie the same at the opposite edge thereof, and operating mechanism for the named pivoted section, the parts 45 of the mechanism being mounted on both the main section and said pivoted section.

50 17. The combination with a railway car, of a grain door mounted at the outer side thereof slidably across the door opening thereof, said door including a mounted main section, a door section mounted to have slidable engagement with the top edge of the main section, a door section pivoted on the main section at the lower portion thereof, a flange mounted on one of the jambs of the doorway extending substantially the full height thereof and spaced from and paralleling the outer wall of the car, and a return hook portion on each of the corresponding edges of the several door sections adapted in the closed position of the door to engage behind the said flange forming a grain-tight joint at said jamb.

55 18. The combination with a railway car having a doorway in its wall, of a door to extend across said doorway, the same including a shiftable main section, a member secured to the car wall at one side of the doorway to receive into it an edge of said main section, a hook member secured to the car wall at the other side of the doorway extending along the opening thereof, a hook member affixed to the opposite edge of the main door section adapted to engage the said hook member at said doorway in the closed position.

- sition of the door, said door section having a recess in its lower edge creating an opening for discharge of grain, a second door section for closing the opening, the same overlying a part 5 of the main door section and pivoted to the latter, and two cooperating portions, each carried by one of the sections, the same adapted when operated to swing the second section with respect to the main section.
- 10 19. The combination with a railway car and its doorway, of a door including a shiftable main section comprising two spaced parallel portions, a member secured to the car wall at one side of and extending along said doorway to receive into 15 it the edges of the spaced portions at one edge of the door, a hook member affixed to the car wall at the other side of the doorway extending along the same, one of the said portions of the door having a hook to engage said hook member forming a grain-tight joint, said door having a 20 recess in its lower edge creating an opening for the discharge of grain, and a second door section pivoted at one end upon the main section for covering said opening and adapted to be shifted 25 between said spaced portions of said main section.
20. The combination with the wall of a railway car having a doorway, of a supported and guided main door mounted on the outer side 30 thereof for closing the doorway, means below the doorway to engage the lower portion of the door for preventing the latter swinging away from the doorway, said door having a recess in its lower portion at the floor of the car, a second 35 door adapted to cover said recess and to rest upon said floor, its marginal edges at the main section overlying the latter at said recess, said second door being pivotally mounted at one end upon the main door, and intermeshing gearing 40 members mounted separately on the door sections adapted in operation to tilt the named second door with respect to the said main door.
21. In combination with a car having a doorway in its side, and an overhead track, of a main door section supported and guided on said track, a second door section pivoted at one end there-to extending below its lower edge, a gear member mounted on each of the sections, each in a fixed mounting, one meshing with the other adapted in the operation of one of them to transmit movement to the other for tilting the said second section with respect to the said main section, a third door section slidable upon said track 10 and engaging the edge of the main door section opposite that having the pivoted section, and mechanism carried by the main door section for securing that section and the named third door 15 section relatively and relatively to the car.
22. A grain door comprised in a single article consisting of a main door section, a second section pivoted at one end near one of the side edges of the main section, and a gear member 20 mounted on each of the door sections meshing one with the other and of a type to fix the second section in any position of adjustment.
23. A grain door comprised in a unitary structure consisting of a main door section having a 25 recess in one edge thereof, a second door section pivoted at one edge to an edge of the main section, and a gear member mounted on each of the door sections meshing one with the other and a type to hold the second section in any position of adjustment.
24. A grain door comprised in a unitary structure consisting of a main door section having a recess in one edge thereof, a second door section pivoted at one edge to an edge of the main section to cover said recess, a gear member mounted on each of the door sections at the pivotal mounting of the said second section and meshing with each other, and a third door section slidably engaging the main door section at its edge 40 lying opposite the edge having such recess.

BRYAN J. O'NEILL.
